(57) **CLAIM**

The ornamental design for a brick stack model construction component, as shown and described.

DESCRIPTION

FIG 1 is a perspective view of the brick stack model construction component.

FIG. 2 is a top plan view thereof.

FIG. 3 is a bottom plan view thereof.

FIG. 4 is a front elevational plan view thereof.

FIG. 5 is a rear elevational view thereof, wherein portions of the drawing shown in broken lines form no part of the claimed design.

FIG. 6 is a left side elevational view thereof; and,

FIG. 7 is a right side elevational view thereof.

1 Claim, 4 Drawing Sheets*FIG. 1*

FIG. 2

FIG. 3

FIG. 4

FIG. 5

FIG. 6

FIG. 7
